United States Patent Office.

ARTHUR W. BROWNE, OF BROOKLYN, NEW YORK, ASSIGNOR TO
MARY A. VAN ALEN, OF SAME PLACE.

Letters Patent No. 91,208, dated June 15, 1869.

IMPROVEMENT IN LAMP-BURNERS.

The Schedule referred to in these Letters Patent and making part of the same.

To all whom it may concern:

Be it known that I, ARTHUR W. BROWNE, of the city of Brooklyn, in county of Kings, and State of New York, have invented and made a certain new and useful Improvement in Lamp-Burners; and I do hereby declare the following to be a full, clear, and exact description of the said invention, reference being had to the annexed drawing, making part of this specification, wherein—

Figure 1 is a vertical section of said lamp-burner, transversely of the shafts of the wick-raisers.

Figure 2 is a similar section of the burner, at right angles to the section, fig. 1.

Figure 3 is a sectional plan, at the line xx .

Figure 4 represents the wick, in the shape it assumes in the burner.

Similar marks of reference denote the same parts.

My invention relates to a burner, in which a flat wick is introduced up through the lower end of the wick-tube, in a flat, folded condition.

The wick is opened, to pass a lateral opening, through which air is admitted to a central tube, and then the wick is brought into a circular form, so that the flat, folded wick is employed in an argand-burner.

The wick-raiser acts upon the wick, when in the folded condition, and the air is directed upon the outside of the flame, by the glass chimney, the interior draught being taken from within a conical chamber, having air-inlet openings at or near the base.

In the drawing—

a is the base of the burner, which is to connect with the reservoir, by a screw, or otherwise.

Through the base, a , the lower part b of the wick-tube passes.

The wick-tube, at this point, is of a size and shape to pass the wick c in the double, or folded condition, illustrated in fig. 4.

At this part of the wick-tube, I apply the wick-raisers d d' .

These wick-raisers are made of pairs of pointed wheels, set on the shafts e e' , so that the points lock into each other; and the wheels and shafts turn together, although the power to rotate is only applied by the button f , to the shaft e .

These wick-raisers act through slots in the wick-tube.

This wick-tube is extended to near the top of the burner, at which point it is circular.

Between the circular top and the lower part of the wick-tube, said wick-tube is spread, to conform to the external shape of the wick, as it is opened out from its

folded form, and brought into a circular shape outside of, or around the central air-tube g .

This central air-tube g is, at its upper end, circular, and extends downward, and curves out sidewise, in an elongated, or flattened form, as shown at h , the area of the elongated opening corresponding, or nearly so, to that of the round upper end of the air-tube; and at the point where the elongated portion of the air-tube g passes out through the side of the tube b , the parts are to be united firmly, to prevent the escape of liquid hydrocarbon, or the vapors thereof.

Around the wick-tube b , there is a conical case, k , that is either perforated at its lower end, or connected otherwise by arms, or braces, with the wick-tube b or base, a , so that air can pass freely into the space, and go up through the central air-tube g .

Around this case k the chimney-holder l is placed.

This is made so as to sustain the glass chimney m , and allow a current of air to pass up between the chimney m and the conical case k , to produce a perfect combustion on the outside of the flame.

The glass chimney should have a contraction, or neck, to deflect the air upon the outside of the flame.

I do not claim a flat wick in a lamp-burner, that bends said wick into a circular form, for an argand-flame, as that has before been employed in the lamp of T. Adams, patented September 16, 1868; nor do I claim two or more wicks brought together into an argand-form, (see Letters Patent granted to me, February 25, 1868, and Young's Vesta-lamp, described in Webster and Park's Encyclopedia of Domestic Economy, page 190, figure 139*.)

In my present lamp, the wick is of one piece of material, folded together where the wick-raisers act upon it, and then spread, to pass the air-tube of the argand-burner, which is not the case with either of the before-named lamps, and hence the wick can be raised with uniformity all around.

What I claim, and desire to secure by Letters Patent, is—

The lamp-burner, constructed with the wick-tube b , air-tube g , and wick-raisers, in the manner specified, so that the flat wick passes in a folded condition, through the wick-tube and wick-raisers, and is then spread into a round form at the argand-flame, as specified.

Dated this 22d day of March, A. D. 1869.

A. W. BROWNE.
